UNITED STATES PATENT OFFICE

JOHANNES JOHANNESSEN, OF JERSEY CITY, NEW JERSEY

CRANK-SHAFT-GRINDING MACHINE

Application filed March 31, 1928. Serial No. 266,206.

The present invention relates to grinding machines and has for its prime object to provide a machine of this nature which is especially well adapted for grinding crank shafts and the like.

Another very important object of the invention resides in the provision of a machine of this nature having suitable adjustments to accommodate different sized crank shafts and the like.

A still further very important object of the invention resides in the provision of a machine of this nature which is simple in construction, strong and durable, easy to manipulate, compact and convenient and thoroughly efficient and reliable in operation.

With the above and numerous other objects in view, as will appear as the description proceeds, the invention resides in certain novel features of construction, and in the combination and arrangement of parts as will be hereinafter more fully described and claimed.

In the drawing:

Figure 1 is a front elevation of the machine embodying the features of my invention.

Figure 2 is a top plan view thereof.

Figure 3 is a sectional view of the slidable holder.

Figure 4 is a vertical transverse sectional view, taken substantially on the line 4—4 of Figure 2, looking in the direction of the arrow.

Figure 5 is a detail elevation showing the crank disc and shaft therefor.

Figure 6 is a face view of the crank disc.

Figure 7 is a detail vertical section, taken substantially on the line 7—7 of Figure 2.

Figure 8 is a detail section taken substantially on the line 8—8 of Figure 3, and

Figure 9 is a detail elevation of the rocking guide.

Referring to the drawing in detail, it will be seen that the numeral 5 denotes a bed, along one longitudinal edge thereof rises therefrom a head stock 6, which is fixed to the bed, as at 7, and a tail stock 8, which is slidable in a T-slot 9, being adjustable by suitable conventional means 10. These stocks 6 and 8 are provided with live center pins 11 and 12 respectively. A worm gear 14 is

rotatable about the dead center pin 11 and meshes with a worm 15, the shaft 16 of which is journaled in the bearings 17, on the base of the head stock 6. A lug 18 is formed on the worm gear 14 and has a screw 19 engaged therein for fixing a lazy dog 20 thereto. This lazy dog, of course, is clamped on crank shaft 21, which is mounted between the live center pins 11 and 12, for rotation therebetween. A hand wheel 22 is mounted on the forward end of the shaft 16 for rotation thereof. A shaft 23 is journaled in a fixed bearing 24, on one of the pair of the longitudinally extending V-guides 25. A gear 26, on one end of this shaft 23 meshes with a pinion 27 on the rear end of the shaft 16. The rear end of the shaft 23 has a crank disc 28 fixed thereto. One end of this crank disc is provided with a dove tailed groove 29 receiving a dove tailed slide 29 which is held in adjusted position by means of set screw 30.

This slide 29 is provided with suitable indicia for the purpose of indicating the throw of the crank pin 31 thereon.

A block 32 is slidable along the V-guides 25 and has rising therefrom spaced ears 33, for rockably receiving therebetween one end of a rod 34, the other end of which is engaged on the crank pin 31, so that when the crank disc is rotated, the block 32 reciprocates back and forth along the V-guides 25 on the bed 5.

A carriage 36 is also slidable on the V-guides 25 and has an opening 37 through which the connecting rod 34 moves. This carriage is provided with another opening 38 to receive a rod 39, which is fixed to the block 32 and is anchored in the opening 38 by means of set screws 40. This carriage is provided with a bore 41 for rockably receiving a pin 42, extending from a rocking guide 43 having a dovetailed groove 43' therein. A holder 44 is provided with a dove tailed end portion 45 slidable in the groove 43 and with a circular head 46, in the nature of a ring, formed in two segments hinged together as at 47, and held in closed relationship by releasable means 48. The crank pin of the crank shafts extends through the ring head 46, and guide pins 49 and 50 are mounted in the ring head, the pin 50 being spring 100

pressed, as is indicated at 51 and the spring being adjustable by a screw 52.

A shaft 53 is journaled through a sleeve 54, slidably mounted in the holder 44 and also through a bearing 55, engaged on the extremity of the dove-tailed end 45. On the end of the shaft 53, within the ring head 46 there is mounted a grinding element 56. The shaft 53 may be driven by a flexible shafting, from any suitable motor or the like, or the motor may be fixed to the extremity of the arm 45. A pocket 58 is provided in the holder 44, and has rockable therein, as at 59, a gear segment 60, meshing with rack teeth 61 on the sleeve 54. A shank 62 projects from the gear segment 60 and is rockably engaged, as at 63, with a sleeve 64 threaded on a rod 65, rotatable in a lug 66, projecting from the head 46, and having hand actuating knob 67. By the rotation of this shaft 65, therefore, the gear segment 60 is rocked, to move the sleeve 54, so as to slide the shaft 53, thereby moving the grinding element 56, toward and away from the crank of the crank shaft 21.

The crank shaft 21 is rotatably engaged on the dead-center pins 11 and 12, by adjusting the tail socket 8 in the usual well known manner. The ring head 46 is engaged about the crank pin of the crank shaft 21, by swinging open the hinged segment thereof and the spring pressed pin 50 will cause the pins 49, 49 and 50 to properly hold the head 46 about the crank pin of the crank shaft and then by turning the knob 67, the grinding element 56 may be engaged with the crank pin of the crank shaft.

The operator then turns the hand wheel 22, imparting reciprocatory motion to the block 32 and simultaneously rotating the crank shaft 21. The reciprocatory motion imparted to the block 32 is imparted to the carriage 36 through the rod 39 and holder 44 therefore moves back and forth along the crank pin of the crank shaft and rocks as said crank revolves, thereby truing the crank pin. Obviously, the slide 29 should be adjusted to accommodate the length of the crank pin, and this may be ascertained by the indicia provided on said slide as clearly shown in Figure 6.

It is thought that the construction, operation, utility and advantages of this invention will now be quite apparent to those skilled in this art without a more detailed description thereof.

The present embodiment of the invention has been disclosed in detail, merely for the purposes of exemplification, since it attains, in actual practice, the features of advantage enumerated as desirable in the statement of the invention and the above description.

It will be apparent that changes in the details of construction, and in the combination and arrangement of parts may be resorted to,

without departing from the spirit or scope of the invention as hereinafter claimed or sacrificing any of its advantages.

Having thus described my invention, what I claim as new is:

1. In a machine of the class described, a bed, a head stock and tail stock on the bed, means for adjustably mounting the tail stock, said head stock and said tail stock being provided with live center pins, a gear rotatable on the live center pin of the head stock, a lazy dog for driving the crank shaft from the gear, means for rotating the gear, a carriage reciprocably mounted on the bed, a guide rockable on the carriage, a holder slidably in the guide, a grinding element in the holder, means for associating the holder with the crank of the crank shaft to move therewith, a shaft journaled in the holder for operating said grinding element, and means for reciprocating the carriage through said gear rotating means.

2. In a machine of the class described, a bed, a head stock and tail stock on the bed, means for adjustably mounting the tail stock, said head stock and said tail stock being provided with live center pins, a gear rotatable on the live center pin of the head stock, a lazy dog for driving the crank shaft from the gear, means for rotating the gear, a carriage reciprocably mounted on the bed, a guide rockable on the carriage, a holder slidably in the guide, a grinding element in the holder, means for associating the holder with the crank of the crank shaft to move therewith, a shaft journaled in the holder for operating said grinding element, and means for reciprocating the carriage through said gear rotating means, and means for adjusting the grinding element.

3. In a machine of the class described, a bed, a head stock and tail stock on the bed, means for adjustably mounting the tail stock, said head stock and said tail stock being provided with live center pins, a gear rotatable on the live center pin of the head stock, a lazy dog for driving the crank shaft from the gear, means for rotating the gear, a carriage reciprocably mounted on the bed, a guide rockable on the carriage, a holder slidably in the guide, a grinding element in the holder, means for associating the holder with the crank of the crank shaft to move therewith, a shaft journaled in the holder for operating said grinding element, means for reciprocating the carriage through said gear rotating means, means for adjusting the grinding element, said means for reciprocating the carriage, comprising a block slidable on the carriage, an adjustable connection between the block and the carriage, a rod pivotally engaged with the carriage, a crank disc, means for rotatably mounting the crank disc, means for rotating the crank disc from the said gear rotating

means, a slide adjustably mounted in the crank disc, means for holding the slide in different adjusted positions, and a crank pin extending from the slide and engaged with the
5 rod.

In testimony whereof I affix my signature.

JOHANNES JOHANNESSEN.
